(57) **CLAIM**

The ornamental design for a thimble for rope eye substantially as shown and described.

DESCRIPTION

FIG. 1 is a top, front, right isometric view of a thimble for rope eye shown in an environment of actual use attached to a rope eye;

FIG. 2 is a top, front, right isometric view thereof;

FIG. 3 is a rear, bottom, right isometric view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a top, front, right isometric view of a second embodiment of the thimble with rope eye;

FIG. 11 is a rear, bottom, right isometric view of the rope eye with thimble of FIG. 10;

FIG. 12 is a front elevation view thereof;

FIG. 13 is a rear elevation view thereof;

FIG. 14 is a right side elevation view thereof;

FIG. 15 is a left side elevation view thereof;

FIG. 16 is a top plan view thereof; and,

FIG. 17 is a bottom plan view thereof.

The broken lines shown in FIG. 1 are for purposes of illustrating use and environment only and form no part of the claimed design. The broken lines in FIGS. 10-17 illustrate unclaimed features of the design and form no part of the claimed design. The dot-dash lines in FIGS. 10-17 depict an unclaimed boundary between claimed and unclaimed portions of the present design.
